UNITED STATES PATENT OFFICE.

HENRY HOPKES, OF DETROIT, MICHIGAN, ASSIGNOR TO MILTON G. GOFF, OF DETROIT, MICHIGAN.

KNIFE SHARPENER.

Application filed August 24, 1920. Serial No. 405,611.

To all whom it may concern:

Be it known that I, HENRY HOPKES, a citizen of the United States of America, residing at Detroit, in the county of Wayne 5 and State of Michigan, have invented certain new and useful Improvements in Knife Sharpeners, of which the following is a specification, reference being had therein to the accompanying drawings.

10 This invention relates to a knife sharpening device, and my invention aims to provide a simple, durable and inexpensive tool that may be easily and quickly manipulated to sharpen the blade of a knife, pair of scissors 15 or other cutting implement, without any danger of the blade being provided with a wire edge or otherwise injured.

My invention further aims to provide a knife sharpener embodying opposed disks 20 frictionally held from rotation but adapted to be turned to present successive points of the edges in contact to provide blade engaging surfaces, thus permitting of the tool being repeatedly used without becoming un- 25 duly worn or dull.

The mechanical construction entering into the tool will be hereinafter described and then claimed, and reference will now be had to the drawing wherein—

30 Figure 1 is a side elevation of the tool, partly broken away and partly in section;

Fig. 2 is a front elevation of the same;

Fig. 3 is a side elevation of the detached tool frame;

35 Fig. 4 is a front elevation of the same, and

Figs. 5 and 6 are detail views of a rotary sharpening device.

In the drawing, the reference numeral 1 40 denotes a handle, preferably made of wood and the outer end of said handle has a head or peripheral bead 2 and a central cylindrical bore or recess 3.

45 4 denotes a comparatively flat and substantially rectangular metallic frame having the inner end thereof provided with a tang 5 which may be driven into the recess 3 to engage in opposed walls of the recess, as at 6 and thus prevent the frame 4 from rotating relative to said handle. The frame 4 abuts the head or outer end of the handle 50 and said frame has a set of openings 7 and an open slot or kerf 8 extending between

the set of openings to provide clearance for a blade 9^a adapted to be sharpened by the 55 tool.

Mounted or journaled in the openings 7 of the frame 4 are tubular rivets or spindles 9 supporting hardened cutters or sharpening disks 10 which are loose on the rivets or spindles when said rivets or spindles are fixed in the frame, or the disks may be fixed on the rivets or spindles when the latter are loose in the frame. In either instance the rivets or spindles have heads 11 to prevent displacement of the disks 10 relative to the frame 4, whereby said disks will be maintained in opposed relation at the side of the frame 4 with the peripheries thereof contacting or approximately so, as shown in 70 Fig. 1. The tubular rivets or spindles are flanged over the disk in each instance on one side and flanged over the aperture of the frame 4 on the opposite side, and these flanged ends of the tubular rivets tightly engage the disk and frame frictionally holding the disks from rotation in operation but permitting the disks to be turned by an instrument, as for instance a pair of pliers applied to one of the disks with sufficient 80 pressure to turn one disk or the other thus bringing different points of the peripheries of the disks into engagement at the center whereby new cutting edges are positioned for use. The edges of the disks 10 85 are in the plane of the slot or kerf 8 and the blade 9^a can be moved back and forth against the disks 10, at the contacting peripheries thereof, or the tool may be moved back and forth over the blade. In either instance, the opposed cutter and sharpening members are adapted to sharpen the cutting edge of the blade 9^a, and since the disks 10 are rotatable it is obvious that different surfaces thereof may be presented to the blade 95 9^a.

It is apparent that the recess 3 may be provided with a suitable filler to assist in holding the frame 4, and that the metallic parts of the tool may be made of the best 100 material finished so as not to corrode.

One embodiment of my invention has been illustrated but it is to be understood that the construction is susceptible to such changes as fall within the scope of the 105 appended claims.

What I claim is:—

1. A tool for sharpening blades which may be drawn across the blade being sharpened, comprising a substantially flat metallic frame having a pair of centrally apertured portions at the end therof, there being a slot extending between said portions from the end thereof to a distance beyond a horizontal line passing through the centers of 5 said apertures in said apertured portions, a single flat cutting disk centrally fixed to each of said apertured portions, and a fastening device passing through each aperture and engaging each disk for retaining the 10 same in position with one surface thereof lying against a surface of the frame, the two disks being disposed in the same plane and in contact at the periphery therof, and a handle projecting from said frame disposed 15 in a plane parallel with the flat surfaces of said disks and having a center line passing between said disks at right angles to the fastening means therefor.

2. A tool for sharpening a blade, in which 25 the tool may be drawn across the blade being sharpened, comprising a substantially flat metal frame having a pair of apertured portions at the end thereof, there being a slot extending between said portions from 30 the end to a distance beyond a line passing through the center of said apertures in said portions, a single cutting disk adapted to be secured to each of said por-

tions, a means passing through said apertures in said portions and through an aperture 35 in each of said disks for securing said disks to the holder, the two disks lying in the same plane with their peripheries in contact, and a handle projecting from said frame disposed in a plane parallel with the 40 sides of said flat disks and having a center line passing between said disks at a right angle to said fastening means for the disks.

3. A tool for sharpening blades adapted to be drawn across a blade being sharpened, 45 comprising a substantially flat metallic frame having a pair of separated portions at the end thereof, a single flat cutting disk carried by each of said portions, the metallic frame having a slot open at its outer 50 end extending between said separated end portions and to a distance beyond a horizontal line passing through the axis of each of said disks, said two disks being disposed in the same plane and in contact at the peripheries thereof, and a handle projecting 55 from said frame disposed in a plane parallel with the flat surfaces of said disks and having a center line passing between said disks.

In testimony whereof I affix my signature in presence of two witnesses.

HENRY HOPKES.
